United States Patent Office.

RICHARD R. MILES, OF WABASH, INDIANA.

Letters Patent No. 98,085, dated December 21, 1869.

IMPROVEMENT IN TAILORS' CRAYON-SHARPENERS.

The Schedule referred to in these Letters Patent and making part of the same.

To all whom it may concern:

Be it known that I, RICHARD R. MILES, of Wabash, in the county of Wabash, in the State of Indiana, have invented a new and useful Mode of Combining Together a Tailor's Weight, Tailor's Crayon, and Tailor's Crayon-Sharpener; and I hereby declare that the following is a full, clear, and exact description of the construction, operation, and uses of the same, reference being had to annexed drawings, of which—

Figure 1 represents a plan or top view of my invention;

Figure 2, a transverse vertical section of the same; and

Figure 3, a similar partial section in a plane at right angles with that of fig. 2.

The object of my invention is to afford the tailor a simple, easy, and cleanly method of sharpening the crayon, without liability to scatter the dust therefrom upon the goods, a support for the crayon when not in use, and a weight for holding down the cloth while under manipulation.

In the drawing—

A is a hollow vessel, of any ornamental form, of a size to be conveniently handled, of a weight sufficient to answer the purpose for which it is intended, and of any suitable material. Its neck *a* is fitted with a stopper, B, also ornamental, which may be screwed in, or otherwise secured, so as to be tight, and serve as a handle, and yet be readily removed, when it shall be necessary to throw out the contents of the vessel A.

The stopper B has an angular or V-shaped notch or groove, *b*, across its top, the sides of which will have a slope, corresponding with the required bevel of the faces of the crayon-edge, as seen at *b*.

In the bevelled faces of the notch *b*, and opposite to each other, are set a series of knife-edges or file-faces, C C, so that the edges of one will cut in the opposite direction from the edges of the other. These cutting-faces do not extend the whole length of the notch *b*, and do not quite touch each other at their lower edges, but extend only so low down in the notch *b* as to leave a narrow slit or opening between them,

through which the products of the crayon-trimming may fall into the interior of the hollow vessel A, through the opening *c*, extending from the slit between the cutting-faces down through the stopper B, as seen in figs. 2 and 3.

By simply drawing the crayon backward and forward between the cutting-faces C, it will receive a double bevel, corresponding with their inclination and that of the sides of the notch or groove *b*, and this last terminating in a mere line at each end of the cutters, and below their edges, will permit the crayon to be dressed to as thin an edge as the tenacity of its material will permit. In use practically, this will be on the cutter's board, and hold down the cloth in the act of cutting.

When the crayon is blunt or crooked, or has uneven edges, the workman, without leaving his work, can sharpen his crayon, by moving it back and forth through the acute bevel, and bring it to a straight, sharp, and equally-bevelled edge, the dust from the crayon, in the act of sharpening, falling into and remaining in the chamber. When so full as to be inconvenient, the top can be removed, and the chamber emptied.

The acute bevel will form a rest for the crayon, when not in use.

With this device, the following advantages are secured. In cutting, the weight, crayon, and sharpener will always be together, and the crayon can be kept sharp, straight, and with an even and equally-bevelled edge, insuring fine, clear lines, and the dust caused by sharpening will not soil the hands nor be scattered on the cloth.

What I claim as my invention, and desire to secure by Letters Patent, is—

The hollow weight A, with its stopper B, provided with the bevelled notch *b*, cutting-faces C C, and opening *c*, all combined and arranged as described, for the purpose set forth.

RICHARD R. MILES.
